Primary Examiner — George D. Kirschbaum
Assistant Examiner — Antoinette Martine Suiter

(57) **CLAIM**

The ornamental design for a part of a bicycle computer as shown and described.

DESCRIPTION

2. Part of a bicycle computer

2.1 : Perspective

2.2 : Back

2.3 : Right

2.4 : Bottom

2.5 : Front

The design represents a part of a bicycle computer. The dash-dash broken lines represent portions of the article that form no part of the claimed design.
